UNITED STATES PATENT OFFICE.

JOHN WILLIAM NASMITH, OF HEATON MERSEY, ENGLAND.

STAPLING-MACHINE.

1,192,446.

Specification of Letters Patent. Patented July 25, 1916.

Application filed August 2, 1910. Serial No. 575,132.

To all whom it may concern:

Be it known that I, JOHN WILLIAM NASMITH, of Heaton Mersey, in the county of Lancaster, England, have invented certain new and useful Improvements in Stapling-Machines, of which the following is a specification.

My invention relates to machines employed to cut, form, and drive the staples which fasten in the ends of wire-bound boxes, the said boxes being composed of sheets and cleats united by binding wires.

In early machines the staple was driven from the outside of the box through the cleats and into the sheets forming the ends of the boxes and in such machines the staple-forming and driving devices could be united at the outer end of the upper jaw while inside the box the end of the lower jaw contained only the anvil for the purpose of turning the ends of the staples and preventing them from protruding into the box. It has been proved by practice to be much better to drive the staple from inside the box through the sheet and into the cleat; this method assuring a stronger box because the comparatively thin sheets are engaged by the bend of the staples while the thicker cleats receive the shanks of the same. As the staples must be driven into the center of the cleat close to the side and bottom of the box, the space for mechanism is limited and in the attempts to operate in this way the staple cutting and forming device has been separated from the driving device, the staples being formed at one end of the machine and then passed by complicated and expensive mechanism to a driving device situated in the extreme point of the lower jaw of the machine, the said jaw being made narrow and pointed to reach the corner of the box. Such an arrangement has many disadvantages in practice.

The term "jaw" is used above because in machines as heretofore constructed it has been customary to so refer to the two members one of which carries the staple applying devices and the other of which carries the anvil mechanism. In the following description however the staple applying member will be simply referred to as the operating member instead of a jaw.

In machines of this kind it has been proposed to arrange suitable forming and driving mechanisms on the end of a single jaw or operative member adapted to be inserted

into the box to drive staples outward through the walls and into the cleats. Such known machines are, however, open to the objection that the box does not receive a staple support, further and more important drawbacks being only one staple forming and driving device can be used in each box and that the latter has to be twisted in order to drive staples near the corners of the boxes.

According to this invention two or more jaws or operating members are arranged a suitable distance apart, preferably with parallel outer faces each carrying a guiding bar, and inner faces each carrying known staple forming and driving mechanisms so arranged that the staples are driven as close as possible to the outer guiding bars, that is to say, as far as possible out of the center line between the jaws or operating members. When a box is in position on the operating member for driving a staple into the material near a corner of a box the nose of said member should fit fairly closely into the said corner; this might prevent the wire for the staple from being fed sufficiently far past the shear, so, to allow room for a sufficient length of wire to be fed forward, the stapling mechanism is inclined relatively to the walls of the box, the increased space between the wall and adjacent stapling mechanism caused by their divergence being sufficient for the object in view.

These and other features will now be described with reference to the accompanying drawings in which one construction of stapling machine according to this invention is shown by way of example.

In these drawings, Figure 1 is a plan of the lower operating member, which goes inside the box; Fig. 2 is an elevation of the inner face of one of the arms, and its plate, and the mechanism supported thereby; and Fig. 3 is a diagrammatic view showing the ends of the staples in relation to the ends and sides of the plates.

B is a portion of the bottom of the box, c, c are cleats, and e is a portion of an end sheet; the staples 3 are driven from the inside of the box through the end sheets and into the cleats. The operating member includes two arms 1, each having an extension or plate 2 to support the mechanism presently described, said arms and supporting plates being fixed a considerable distance apart on a main frame (not shown) so as to form a broad square-nosed end a. Since

wire bound boxes are rarely less than 12" wide the total width a may be several inches and still be easily introduced into a box of minimum width. On the inner cheek of each plate 2 a staple cutting, forming, and driving device is mounted. This device is of the usual kind and is therefore only shown in outline at d ; it is so arranged that the exit for the staples 3 is close to each corner 4, 5 (Figs. 1 and 3) of the end a and instead of driving the staples normally to the face of the material the drivers are inclined slightly to enable a long staple to be obtained.

15 The machine is provided with two treadles and clutches, and two anvils (or one broad one) in the end of the upper member (not shown) so that the operator may drive the staples along one side of the box by operating say the stapling device that drives staples at 4, and he may drive the staples along the bottom of the box by operating simultaneously both stapling devices and then drive those along the other side of the box 25 by using the other stapling device at the corner 5. It is obvious that in using both stapling devices in crossing the bottom of the box this part of the work is done twice as quickly as formerly, thus increasing the 30 productive capacity of the machine by driving two staples at one stroke. Another advantage is that the box is more stable and is supported better by resting on the broad square-nosed end of the lower operating member than when resting on a pointed end of very small area.

The wire may be fed and the cutting, forming, and driving devices may be operated in any suitable way. In the construction shown the following mechanism is employed: Rods 6, 7 are reciprocated from eccentrics set in motion by clutches operated from treadles in the usual way; they are connected to the double armed levers 8, 9 40 pivoting on the cross shaft 8'. To one arm is fastened the toothed sector 10, which operates the shear, former, and driver in the usual way. The staple wires 11, 12 pass over milled disks 13, 14 and are nipped between these and smaller disks 13^a mounted above on eccentric studs in the usual way. The staple wires 11, 12 pass over milled disks 13, 14 and are nipped between these and smaller disks 13^a mounted above on 50 eccentric studs in the usual way. Fixed on the same studs as the milled disks 13, 14 are ratchet wheels 15, 16 operated by pawls 17, 18 pivoted on studs carried by levers 19, 20, which, in turn, pivot freely on 55 the stud carrying the ratchet wheels. The pawls 17, 18 may be pressed into engagement with their ratchet wheels 15, 16 by leaf springs. The levers 19, 20 are connected by links 30 to levers 21, 22 freely 60 pivoted at their ends 31 and each carrying a

70 bracket or contact member 23, 24 having a bowl attached thereto. The extent to which the levers 21, 22 may follow the horizontal arm of the levers 8, 9 as they fall is limited by any suitable bracket (not shown) fixed on each of the plates 2. After the levers 8, 9 have been drawn to the left by the revolution of the above mentioned eccentrics and have cut, formed, and driven staples they 75 come back to the position shown in Fig. 2 and toward the end of this return stroke their horizontal arms come against the bowls on the brackets 23, 24 and raise the levers 21 and 22. This raising of the levers 21 and 22 turns the feed disks and feeds the wire 80 ready for the next staples. The downward movement of the levers 21 and 22 about their pivots 31 may be caused entirely by their own weight and the weight of the contact members 23 and 24, or springs may be provided to assist this downward movement.

85 Although the drawings show two arms 1, each having a plate 2 it will be obvious that in some cases more than two may be employed in the case of machines working wide 90 boxes exclusively; and that, if desired, the operating member may be above, the box being turned over and the staples driven downward from the inside of the box.

95 What I claim is:—

1. In a stapling machine the combination of a main frame; a plurality of outwardly projecting arms mounted some distance apart upon the frame and with their outer lateral faces approximately parallel; and staple forming and driving mechanisms mounted upon the inner faces of the said arms, said mechanisms being independent of each other for individual operation, and the extremities of the arms with their stapling 100 mechanisms being adapted to be introduced into the inside of a box to drive the staples outward.

110 2. In a stapling machine the combination of a main frame; a plurality of outwardly-projecting arms mounted some distance apart upon the frame; and staple forming and driving mechanisms mounted upon the inner faces of the said arms, said mechanisms being independent of each other for individual operation, and the extremities of the arms with their stapling mechanisms being adapted to be introduced into the inside of a box to drive the staples outward.

115 3. In a stapling machine the combination of a main frame; a plurality of outwardly-projecting arms mounted some distance apart on the said frame; mechanisms for cutting, forming and driving staples, the said mechanisms being situated between the 120 outwardly-projecting arms and adjacent to the outer extremities thereof; and means for feeding wire for the staples to the said cutting mechanisms, the cutting, forming, and driving mechanism of each member being 125 130

independent for individual operation, and the extremities of the arms with their stapling mechanisms being adapted to be introduced into the inside of a box to drive the 5 staples outward.

4. In a stapling machine the combination of a main frame; a plurality of outwardly-projecting arms mounted some distance apart on the said frame; mechanisms for 10 cutting, forming, and driving the staples, the said mechanisms being fixed in an inclined position between the outwardly-projecting arms and adjacent to the outer extremities thereof; and means for feeding 15 wire for the staples to the said cutting mechanisms, the cutting, forming and driving mechanism of each member being independent 20 for individual operation, and the extremities of the arms with their stapling mechanisms being adapted to be introduced into the inside of a box to drive the staples outward.

5. In a stapling machine the combination of a main frame; a plurality of outwardly-projecting arms mounted some distance apart on the said frame; mechanisms for 25 cutting, forming, and driving staples, each of the said mechanisms being mounted on the inner face of one of the outwardly-projecting arms and adjacent to the outer extremities thereof; and means for feeding 30 wire to each of the said cutting mechanisms, the cutting, forming and driving mechanism of each arm being independent for individual 35 operation, and the extremities of the arms with their stapling mechanisms being adapted to be introduced into the inside of a box to drive the staples outward.

6. In a stapling machine the combination 40 of a main frame; a plurality of outwardly-projecting arms of equal length and mounted upon the frame with their outer lateral faces parallel to each other; mechanisms for 45 cutting, forming, and driving staples, the said mechanisms being situated between the outwardly-projecting arms and adjacent to the outer extremities thereof; and means for feeding 50 wire for the staples to the said cutting mechanisms, the cutting, forming and driving mechanism of each arm being independent for individual operation, and the extremities of the arms with their stapling mechanisms being adapted to be introduced into the inside of a box to drive the staples outward.

7. In a stapling machine the combination 55 of a main frame; a plurality of outwardly-

projecting arms of equal length and mounted upon the frame with their outer lateral faces parallel to each other; mechanisms for 60 cutting, forming, and driving the staples, the said mechanisms being fixed in an inclined position between the outwardly-projecting arms and adjacent to the outer extremities thereof, and means for feeding 65 wire for the staples to the said cutting mechanisms, the cutting, forming and driving mechanism of each arm being independent for individual operation, and the extremities of the arms with their stapling mechanisms 70 being adapted to be introduced into the inside of a box to drive the staples outward.

8. In a stapling machine the combination of a main frame; a plurality of outwardly-projecting arms of equal length and mounted 75 upon the frame with their outer lateral faces parallel to each other; mechanisms for cutting, forming, and driving staples, each of the said mechanisms being mounted on the inner face of one of the outwardly-projecting arms and adjacent to the outer extremity thereof; and means for feeding wire 80 to each of the said cutting mechanisms, the cutting, forming and driving mechanism of each arm being independent for individual 85 operation, and the extremities of the arms with their stapling mechanisms being adapted to be introduced into the inside of a box to drive the staples outward.

9. In a stapling machine the combination 90 of a main frame; a pair of arms of equal length extending outwardly from the frame in a horizontal direction, the said arms having their outer lateral faces parallel and being situated some distance apart upon the 95 frame; two sets of mechanisms for cutting, forming, and driving staples, one of the said sets being mounted upon the inner face of one arm while the other set is mounted on the inner face of the other arm, the two sets 100 of cutting, forming, and driving mechanisms being independent for individual operation, and the extremities of the arms with their stapling mechanisms being adapted to be introduced into the inside of a box to 105 drive the staples outward; and means for feeding wire to the two sets of cutting mechanisms.

In testimony whereof I have affixed my signature, in presence of two witnesses.
